CLAIM

The ornamental design for a interfitting towel clip, as shown and described.

DESCRIPTION

FIG. 1 is a top plan view of an interfitting towel clip showing my new design;

FIG. 2 is a front elevational view thereof;

FIG. 3 is a left side elevational view thereof;

FIG. 4 is a right side elevational view thereof;

FIG. 5 is a bottom plan view thereof; and

FIG. 6 is a front elevational view of a second embodiment of the design of FIG. 1 showing the clips interfitted, the individual clips being identical to that embodied in FIGS. -6.
